[57] CLAIM

The ornamental design for a ceiling clip, as shown and described.

DESCRIPTION

FIG. 1 is a perspective view of a ceiling clip showing our new design;

FIG. 2 is a right side elevational view thereof, the left side being identical;

FIG. 3 is a rear elevational view thereof;

FIG. 4 is a front elevational view thereof;

FIG. 5 is a top plan view thereof;

FIG. 6 is a bottom plan view thereof; and,

FIG. 7 is a reduced perspective view thereof, the ceiling element shown in broken lines is for illustrative purposes only, and forms no part of the claimed design.

FIG. 2.

FIG. 4.

FIG. 3.

FIG. 6.

FIG. 5.
